OILING DEVICE

Fred S. Payne, West Orange, N. J.

Application July 23, 1930, Serial No. 470,150

11 Claims. (Cl. 184—21)

The invention relates to oiling devices, and particularly to devices for oiling guide rails in elevator shafts.

An object of the invention is to provide an oiling device movable relatively to a member which is operatively engaged by a part of the oiling device to feed oil when the oiling device moves relatively to the member, the rate at which the oil is fed by the oiling device being regulated by the speed of the oiling device relatively to the said member.

The invention has for another object to provide a pump for pumping oil to a guide rail in an elevator shaft, the pump being operated by a member in engagement with the elevator shaft.

Still another object of the invention is to provide an eccentric engaging a member, the rotation of the eccentric by the member serving to operate an oil pump.

Still other objects of the invention are to provide an adjustable mounting for the eccentric to regulate the action of the pump with relation to the eccentric and to provide the eccentric with a cork periphery which engages a member for rotating the eccentric.

The invention has for a further object to provide an oiling compartment to which the oil is fed by a pump, there being oiling or lubricant members in the compartment which are pressed by springs against an elevator guide rail, or other member. Any excess oil in the oiling compartment is returned to a reservoir leading to the pump.

Another object of the invention is to provide means to feed oil from a device in proportion to the distance traveled by the device, the said means only feeding oil when the device is in motion.

Additional objects of the invention will appear in the following specification in which the preferred form of the invention is described.

In the drawings similar reference characters refer to similar parts in all the views, of which

Figure 1 is a side elevation partially in section illustrating my oiling device as mounted on a shoe for engagement by a guide rail in an elevator shaft.

Figure 2 is a sectional view on the line 2—2, of Figure 1.

Figure 3 is an enlarged sectional view illustrating the pump which serves to feed the oil to the oiling compartment.

Figure 4 is a sectional view on the line 4—4, of Figure 1.

Figure 5 is a sectional view on the line 5—5, of Figure 6, and

Figure 6 is an enlarged side elevation of the eccentric.

By referring to the drawings it will be seen that the oiling device is shown as applied to an elevator shaft having a guide rail 10, a shoe 11 which is mounted on an elevator being positioned to travel on the said guide rail.

The oiling device has a supporting member 12, one end 13 of which is bent upwardly to form a standard, and on this supporting member 12 there is mounted a bearing member 14 to which are pivoted at 15 arms 16, these arms 16 being two in number and one being disposed at each side of the bearing member 14, as illustrated in Figure 2 of the drawings. Each arm 16 has a slot 17 therein and disposed in these slots 17 there is a shaft 18 which is held in adjusted position in the said slots 17 by nuts 19. Disposed between the arms 16 and mounted on the shaft 18 there is an eccentric 20, as best shown in Figures 5 and 6. As will be seen by referring to Figure 5, the periphery 21 of this eccentric is manufactured of cork, the said cork periphery being disposed between the side plates 22 of the eccentric and being held in position by rivets 23 which extend through the side plates 22 and through the cork periphery 21. The hub 24 of the eccentric has upwardly disposed flanges 25 which engage the outer sides of the inner ends of the plates 22 to hold the said plates 22 in position, there being preferably a collar 26 disposed between the plates 22 and also between the hub 24 and the cork periphery 21. This eccentric 20 is mounted on the shaft 18, as has been stated and the shaft with the eccentric is held in adjusted position in the slot 17 by the nuts 19. There is also mounted on the shaft 18 a shield 27 which serves to prevent oil from spattering about the shaft as the cork periphery 21 of the eccentric 20 rotates on the guide rail 10.

Secured to the shield 27 there is a rod 28, the said rod passing through a slot 29 in the standard 13 and having a nut 30 at its outer end beyond the standard 13 to limit the inward movement of the rod 28. There is also a spring 31 mounted on the rod 28 and disposed between the standard 13 and the shield 27 for holding the shield 27 extended with the arms 16 and the eccentric 20 so that the cork periphery 21 of the eccentric will at all times frictionally engage the guide rail 10. This cork periphery 21 is provided to make certain that the eccentric will at all times

rotate because of its frictional engagement with the guide rail 10.

Mounted in bearings in the arms 16 there is a rocker member 32 held in position by pins 33 which extend through openings in the rocker member 32 and which engage the outer sides of the arms 16, this rocker member 32 having secured thereto a piston 34 which extends through a gland 35 held by the usual nut 36 in a pump member 37, the pump member 37 being secured to a pump 38 having an outlet valve seat 39 and an inlet valve seat 40, a ball valve 41 being provided for seating at the outlet 39 and a ball valve 42 being provided for seating at the inlet 40. It will, therefore, be seen that with the arms 16 and by means of the eccentric 20 the piston 34 will be reciprocated, which will draw a fluid inwardly through the inlet 40 and force the fluid outwardly through the outlet 39 to the communicating means 43 leading to the top of an oiling compartment 44. Disposed below the supporting member 12 and secured thereto by straps 45 there is a reservoir 46, the pipe or communicating means 47 extending from the interior of this reservoir 46 to the pump inlet 40.

The oiling compartment 44 is best shown in Figure 4 of the drawings, and it will be seen that this oiling compartment 44 has an opening 48 through which the guide rail 10 is disposed. Contained in the oiling compartment there is a plurality of oiling members 49 and 50 which are preferably three in number, there being two oiling members 49, one disposed at each side of the guide rail 10, and an oiling member 50 disposed at the end of the guide rail 10. Leaf springs 51 are provided for pressing the oiling members 49 and 50 against the guide rail 10. As has been stated the pipe or communicating means 43 leads to the oiling compartment 44. There is also a pipe or communicating means 52 leading from the side of the oiling compartment 44 to the reservoir 46.

As will best be seen by referring to Figure 3 of the drawings, the pump member 37 has a threaded stud 53 extending through an opening 54 in the standard 13, there being nuts 55 on this threaded stud 53 which serves to hold the pump member 37 in position on the standard 13. The oiling compartment 44 is secured to the supporting member 12 by means of clamps 56 which are held in position by screws 57. The supporting member 12 has a depending member 58 which engages the sides and the inner end of the shoe 11 and which is secured to the shoe 11 by screws 59.

What is claimed is:

1. In an oiling device, a pivoted arm extending longitudinally of an elevator shaft, an eccentric mounted for rotating on the pivoted arm for engaging a member of the elevator shaft, a shield mounted on the pivoted arm and disposed partially around the eccentric, resilient means for engaging the shield for holding the eccentric extended, a pump, means by which the pivoted arm is adapted to operate the pump, an oiling member adjacent a member of the elevator shaft with which the pump outlet is connected, and a reservoir with which the oiling member is connected, the reservoir being connected with the pump inlet.

2. In an oiling device, a standard with an opening, an arm pivoted relatively to the standard and disposed longitudinally of a guide rail, an eccentric for engaging the guide rail, the eccentric being adjustably and rotatably mount-

ed on the pivoted arm, a shield adjustably mounted on the pivoted arm and disposed partially around the eccentric, a rod secured to the shield and disposed in the opening in the standard, a spring mounted on the rod and disposed between the standard and the shield for holding the shield extended with the arm and the eccentric, a pump, and means by which the pivoted arm is adapted to operate the pump to feed a lubricant to the guide rail.

3. In an oiling device, a standard with an opening, an arm pivoted relatively to the standard and provided with a slot, an eccentric for engaging a member of an elevator shaft, the eccentric being adjustably secured in the slot for rotating relatively to the arm, a shield carried by the arm, a rod secured to the shield and disposed in the opening, a spring mounted on the rod between the standard and the shield, a pump for feeding a lubricant to a guide rail in the elevator shaft, and means by which the pivoted arm is adapted to operate the pump.

4. In an oiling device, a standard with an opening, an arm extending longitudinally of an elevator shaft and pivoted relatively to the standard, the arm being provided with a longitudinally extending slot, an eccentric for engaging a member of the elevator shaft, a shaft adjustably secured in the slot on which the eccentric is rotatably mounted, means for holding the arm yieldingly extended with the eccentric adjacent a member of the elevator shaft, a pump for feeding a lubricant to a guide rail in the elevator shaft, and means by which the pivoted arm is adapted to operate the pump.

5. In an oiling device, a pivoted arm extending longitudinally of an elevator shaft, an eccentric adjustable longitudinally of the arm for rotating on the arm, resilient means for holding the arm yieldingly extended to hold the eccentric in engagement with a member in the elevator shaft, a pump for feeding a lubricant to a guide rail of the elevator shaft, and means by which the pivoted arm is adapted to operate the pump.

6. In an oiling device, a pivoted arm extending longitudinally of an elevator shaft, an eccentric adjustable longitudinally of the arm for rotating on the arm, resilient means for holding the arm yieldingly extended to hold the eccentric in engagement with a member in the elevator shaft, a pump having a piston which is articulated to the arm, and means connected with the pump for feeding a lubricant to the guide rail in the elevator shaft.

7. In an oiling device, an oiling compartment normally disposed adjacent a guide rail of an elevator shaft, a reservoir, a pump, a conduit connecting the pump with the oiling compartment adjacent the top of the latter, a conduit connecting a side of the oiling compartment with the reservoir, a conduit connecting the reservoir with the pump, eccentric means normally engaging the elevator shaft and means cooperating with the eccentric and the pump for operating the latter.

8. In an oiling device, an oiling compartment normally disposed adjacent a guide rail of an elevator shaft, a pump having a piston, a reservoir, a conduit connecting the pump with the oiling compartment adjacent the top of the latter, a conduit connecting a side of the oiling compartment with the reservoir, a conduit connecting the reservoir with the pump, an arm extending longitudinally of the elevator shaft and articulated

to the piston, an eccentric mounted for rotating on the arm by engagement with a member on the elevator shaft, and resilient means for holding the arm yieldingly extended.	ing member, a conduit leading from the pump to the oiling compartment, a reservoir depending from the supporting member and secured thereto, a conduit connecting the reservoir with the pump, and a conduit connecting the oiling compartment with the reservoir.	80
5 9. In an oiling device, a supporting member having a standard, an arm pivoted to the supporting member, an eccentric mounted for rotating on the arm, a pump secured to the supporting member having a piston rod articulated to the arm, means cooperating with the standard and the arm for holding the eccentric yieldingly extended against a member in an elevator shaft, an oiling compartment mounted on the supporting member, and a conduit leading from the pump to the oiling compartment.	11. In an elevator guide rail lubricating device of the type which is bodily carried by and movable with the guide rail engaging shoe as it moves over the guide rail, said device including a lubricant reservoir, a conduit leading from the reservoir and having an outlet adjacent the guide rail, a pump having a reciprocatory plunger for feeding the lubricant from the reservoir through the conduit and from the conduit outlet onto the guide rail, and mechanism including means having continuous rolling contact with the guide rail when the elevator is in motion for imparting reciprocations to the pump plunger, said device further including a return conduit to permit the return of excess lubricant to the reservoir.	85
10 10. In an oiling device, a supporting member having a standard, an arm pivoted to the supporting member, an eccentric mounted for rotating on the arm, a pump secured to the supporting member having a piston rod articulated to the arm, means cooperating with the standard and the arm for holding the eccentric yieldingly extended against a member in an elevator shaft, an oiling compartment mounted on the support-		90
